CLAIM

The ornamental design for in-ceiling speaker, as shown and described herein.

DESCRIPTION

FIG. 1 is a perspective view of a in-ceiling speaker showing our design;

FIG. 2 is perspective view thereof, in its environment; and, FIG. 3 is a front elevational view thereof.

The side and back portions of the in-ceiling speaker form no part of the claimed design.

The broken line showing on FIGS. 1–3 is for illustrative purposes only and forms no part of the claimed design.
